[57] CLAIM

The ornamental design for a reciprocating saw, as shown and described.

DESCRIPTION

FIG. 1 is a top and right rear perspective view of a reciprocating saw showing our new design;

FIG. 2 is a top plan view;

FIG. 3 is a left side elevational view;

FIG. 4 is a bottom plan view;

FIG. 5 is a right side elevational view;

FIG. 6 is a front elevational view;

FIG. 7 is a rear elevational view; and

FIG. 8 is a rear top and right rear perspective view thereof with the handle removed for ease of illustration.

FIG. 4

FIG. 5

FIG. 6

FIG. 7
